(57) **CLAIM**

The ornamental design for a device for removing dead skin from a human foot, as shown and described.

DESCRIPTION

FIG. 1 is a top plan view of a device for removing dead skin from a human foot;

FIG. 2 is a bottom plan view of a device for removing dead skin from a human foot of FIG. 1 showing a plurality of suction elements attached to a bottom surface thereof;

FIG. 3 is a top perspective view of a device for removing dead skin from a human foot of FIG. 1 showing an interior sandpaper type area; and,

FIG. 4 is a side elevational view of FIG. 2 taken along the line 4—4 thereof, showing the suction cup elements attached to the bottom surface.
